UNITED STATES PATENT OFFICE.

SAMUEL E. TIDEY, OF FLORHAM PARK, NEW JERSEY.

WEIGHT-RELEASING CLOCK.

Application filed August 10, 1921. Serial No. 491,141.

To all whom it may concern:

Be it known that I, SAMUEL E. TIDEY, a citizen of the United States, and a resident of Florham Park, in the county of Morris and State of New Jersey, have invented new and useful Improvements in Weight-Releasing Clocks, of which the following is a specification.

This invention relates more particularly to 10 weight-releasing clocks which are employed for operating the dampers of a furnace so as to start the same at a desired time in the morning, although it will be understood that the invention may be used for any purpose 15 to which it is adapted.

The objects of the invention are to provide an improved construction of such a clock in which gearing and an escapement are utilized to reduce the strain of supporting the weight by the releasing mechanism and thus enable it to be more sensitive and durable; to simplify the construction and operation of such a clock; to render the clock more reliable and eliminate unnecessary movement and action; to enable the clock to be easily and readily reset after it has "gone off" or operated; to mount directly upon the idle shaft to which the gearing and escapement are connected a projection or 30 arm fast on said shaft for the attachment of the weight; to enable said shaft to turn backward independent of the gearing and escapement for resetting; to secure an inexpensive and durable construction, and to 35 obtain other advantages and results as may be brought out by the following description.

Referring to the accompanying drawings, in which like numerals of reference indicate the same parts throughout the several 40 views,

Figure 1 is a front view of a furnace clock of my improved construction, connected to a damper lever;

Figure 2 is a rear view of the clock under 45 similar conditions;

Figure 3 shows the releasing mechanism of the clock in side elevation, the frame being shown in section on the line 3-3 of Figure 4, and

50 Figure 4 is a sectional view of the same on line 4-4, Fig. 3.

In said drawings, 1 indicates the upper part of a furnace having a lever 2 connected by a chain 3 to a draft or drafts (not shown) 55 to operate the same upon movement of the lever. A weight 4 upon one end of the lever

2 causes that end to normally swing downward to start the furnace, and I have shown it in Figure 1 held upward by a chain 5 hooked to a furnace clock 6 of my improved construction hung from the ceiling 7 or other fixed support. This arrangement is but typical of the numerous ones with which my clock can be used, and is shown only for purpose of illustration. The lever 2 is even 60 unnecessary, since the chain 5 could extend to a damper or draft, and I intend both the chain and the lever to be representative of any known system or arrangement of chains or levers or both chains and levers, or any 65 known damper or draft operating mechanism to which my improved furnace clock could be applied. Any apparatus of the sort which can be held in position to damp off a furnace by the chain 5 hooked to a clock-operated release of my construction and which will be actuated to start the furnace by release of the chain 5 from the clock, is to be considered within the scope of this invention. Furthermore, my invention is not 70 restricted to furnace clocks, but can be used to release other things than drafts and dampers, of any sort or kind whatever to which my invention is applicable.

The construction of my improved release, 85 which is embodied in the clock 6, is illustrated in Figures 3 and 4 more especially, where 8 indicates the dial holder and 9 a plate mounted thereon by studs 10 and rigidly connected by posts 11 to a spaced 90 parallel plate 12, between which plates the clock works are mounted. The pinion 13 on the minute hand arbor drives the gear 14 to which is secured a pinion 15 which drives the hour hand gear 16. Said pinion 15 95 also drives a gear 17 which carries the rotary cam 18 which co-operates with the fixed member 19 on the alarm-setting arbor 20 to hold the detent 21 in engagement with the escapement arm 22 and keep 100 said escapement 23 locked until the hour for which the alarm is set arrives. When the escapement is released the gear 24 is free to be turned by the gear 25 on the shaft 26 engaging the lantern wheel 27 fast 105 on the arbor of the escapement gear 24, and in an ordinary alarm clock such turning is effected by a spring wound on the said shaft 26. In my improved construction there is no such spring, and the shaft 26 110 merely projects through the rear wall 28 of the clock case and is provided with a

fixed arm 29 which is preferably hooked or curved as shown to receive the chain 5. When the escapement 23 is released and the shaft 26 is free to turn, the weight or pull 5 through the chain 5 upon the arm 29 causes the same to turn or swing downward until the chain slips off and is released. The arm 29 then stops, having moved through only about ninety degrees or less, and upon 10 resetting the device it is necessary only to turn the arm backward through those ninety degrees, or push it upward to its initial position, and hook the chain 5 onto said arm again, such backward turning of 15 the shaft 26 being permitted by the ratchet wheel 30 and pawl 31 on the shaft and gear 25 respectively.

The shaft 26 and connected parts thus turn to a minimum extent by my improved 20 construction, and no actuating means for turning them is required to be embodied in the clock. Simplification of construction and especially of operation is thus secured, and greater durability because of less movement and strain upon parts. 25

Obviously various modifications of construction can be made in manufacturing my improved releasing device, without departing from the spirit or scope of the in-

vention, and I do not wish to be understood as restricting myself except as required by the following claims when construed in light of the prior art. 30

Having thus described the invention, what I claim is:

1. In a weight-releasing clock, the combination of a clock casing, an idle shaft journaled in said casing, a gear connected to said shaft, a radial projection on said shaft outside said clock casing adapted to 40 receive a weight so as to turn said shaft and gear, an escapement for said gear, a detent for said escapement, and clock-work for releasing said detent at a predetermined time. 45

2. In a weight-releasing clock, the combination of a casing, an idle shaft journaled in said casing, a gear connected to said shaft, a lateral arm on said shaft outside said clock casing receiving a weight to turn 50 the shaft and adapted by its angular movement to release the weight as the shaft and gear turn, an escapement for said gear, a detent for said escapement, and clock-work for releasing said detent at a predetermined 55 time.

SAMUEL E. TIDEY.
